UNITED STATES PATENT OFFICE

JOHAN GUNNAR EVERSTAM, OF SUNDSVALL, SWEDEN

LIFTING JACK

Application filed December 24, 1925, Serial No. 77,577, and in Sweden August 5, 1925.

The present invention relates to an improvement in such lifting jacks in which the member which may be raised and lowered by means of the jack mechanism proper, whether said mechanism consists of feeding pawls, cylindrical or conical toothed gearing, or a hydraulic device—supports a rod or the like which is adjustable in the said member and serves to support the load, and which serves the purpose of doing away with the difficult and time-wasting propping up of the lifting jack otherwise often necessary, and which for this purpose may be locked by means of a catch device in the desired position relatively to the up and down movable member, according to the height of the body underneath which the lifting jack is to be placed and which is to be raised by means of the jack. The lifting jacks of this type hitherto used in which the catch device is moved by hand into as well as out of engagement, are encumbered with the disadvantage that one is not able to disengage the catch device when the weight of the load rests on the rod, and it is therefore often difficult to remove the lifting jack after use.

The purpose of the invention is to remove this disadvantage, and the invention consists principally in that there is provided on the frame of the jack a stop which is located in the path of movement of a projection or the like provided on the catch member of the catch device, in such manner that upon lowering of the up and down movable member said projection strikes against the stop and thus moves the catch member out of engagement. The catch device will thus be automatically disengaged as soon as the up and down movable member has been lowered to a certain position, so that the rod will drop down, and the lifting jack becomes free and may be removed. It is advantageous to make the said stop adjustable so that it may be moved into and out of the path of movement of the projection, as may be desired.

In the accompanying drawing a few embodiments of the invention are illustrated by way of example. Fig. 1 shows a side view of a lifting jack according to the invention, and Figs. 2 and 3 show two different eleva-

tions of a slightly modified embodiment of the stop.

In the embodiment illustrated in Fig. 1, 1 denotes the frame of the lifting jack in which the member 2 is movable up and down in the usual manner by means of the lifting jack mechanism proper. In the embodiment illustrated said mechanism is shown as consisting of feeding pawls 18, 19, which engage a rack 3 of teeth on the member 2, and which may be actuated by means of a handle or the like, not illustrated, which is introduced into a sleeve 5, which is pivoted on a pin 4 in the frame 1. The member 2 which may be raised and lowered in this manner, is provided with a laterally projected arm 6 which may be introduced underneath the load which it is desired to lift. In order to avoid the necessity of propping up the lifting jack in case of greater heights of the load to be lifted, there is also provided in the member 2 a slideable rod 7 which supports at its upper end the usual plate 8, which is introduced underneath the load to be lifted. The rod 7 is also provided on one side with teeth 9 which may be engaged by a catch 10 pivoted at the upper end of the member 2 and actuated by a coil spring 20 which tends to move said catch into engagement with the teeth 9. By means of this catch device the rod 7 and plate 8 may thus be adjusted in different positions of height relatively to the member 2, according to the height of the body underneath which the lifting jack is to be placed.

According to the invention there is provided on the frame 1 a stop 11 which is located in or may be moved into the path of movement of a projection 12 on the catch 10, in such manner that upon lowering of the member 2 said projection strikes against the stop 11 and thus turns the catch 10 out of engagement with the teeth 9 on the rod 7. The rod 7 thus becomes free and will drop so far down as it will go into the member 2, after which the lifting jack may easily be pulled aside. In the embodiment illustrated in Fig. 1 the stop 11 has the shape of a stud on a lever 14 which is pivoted on a bolt 13 and which may be turned by means of a handle 15, so that the stud 11 may be moved into or out of the path

of movement of the projection 12, according as it is desired or not to effect automatic disengagement of the catch 10. According to Figs. 2 and 3, however, the stop 21 consists of the larger portion of a bolt 16 which is 5
slidable in two lugs 17 on the frame 1, so that by displacement of said bolt the larger portion 21 may be moved into or out of the path of movement of the projection 22, which is provided at one side of the catch 23, as 10
shown in Fig. 3. In the position of the bolt shown in Fig. 3, the projection 22 may, upon lowering of the member 2, move freely past the smaller portion of the bolt, so that the catch 23 will not become disengaged. If the bolt 16 is displaced to the left in Fig. 3, however, so that the larger portion 21 comes opposite the projection 22, said projection will, 15
upon lowering of the member 2, strike against the portion 21, so that the catch device is automatically disengaged. When the member is again raised, the catch 23 is again turned into engaging position by the spring 20
actuating the same.

25 The embodiments above described and illustrated in the drawing are only to be regarded as examples, and their details may obviously be further modified in several ways without departing from the principle of the 30 invention.

I claim:

35 1. In a lifting jack, the combination of a frame, a member vertically guided and movable up and down in said frame, a jack mechanism for effecting the up and down movement of said member in said frame, a rod 40
slidable vertically in said member and provided with a vertical row of teeth free from engagement with said jack mechanism, a catch device on said up and down movable member adapted to engage said row of teeth on said vertically 45
slidable rod and thereby to lock said rod to said member in a number of different positions, said catch device having a projection, and a stop on said frame located in the path of movement of said projection and adapted upon lowering of said member to engage said projection to move said catch device out of engagement.

50 2. In a lifting jack, the combination of a frame, a member vertically guided and movable up and down in said frame, a jack mechanism for effecting the up and down movement of said member in said frame, a rod 55
movable in said member free from engagement with said jack mechanism, a catch device for locking said rod relatively to said member, said catch device having a projection, and a stop on said frame adjustable in such manner that it may be moved into and out of the path of movement of said projection and adapted upon lowering of said member to engage said projection so as to release said catch device.

60 3. In a lifting jack, the combination of a

frame, a member vertically guided and movable up and down in said frame, a jack mechanism for effecting the up and down movement of said member in said frame, a rod 70
slidable vertically in said member and provided with a vertical row of teeth free from engagement with said jack mechanism, a catch device on said up and down movable member adapted to engage said row of teeth on said vertically 75
slidable rod and thereby to lock said rod to said member in a number of different positions, a spring actuating said catch device so as to move the same into locking position relatively to said rod, said catch device having a projection, and a stop on said frame located in the path of movement of said projection and adapted upon lowering of said member to engage said projection to move said catch device out of engagement.

80 4. In a lifting jack, the combination of a frame, a member vertically guided and movable up and down in said frame, a jack mechanism for effecting the up and down movement of said member in said frame, a rod 85
movable in said member free from engagement with said jack mechanism, a catch device for locking said rod relatively to said member, a spring actuating said catch device so as to move the same into locking position 90
relatively to said rod, said catch device having a projection, and a stop on said frame adjustable in such manner that it may be moved into and out of the path of movement of said projection and adapted upon lowering of said member to engage said projection so as to release said catch device.

95 5. In a lifting jack, the combination of a frame, a member vertically guided and movable up and down in said frame, a jack mechanism for effecting the up and down movement of said member in said frame, a rod 100
slidable vertically in said member and provided with a vertical row of teeth free from engagement with said jack mechanism; a catch device on said up and down movable member adapted to engage said row of teeth on said vertically 105
slidable rod and thereby to lock said rod to said member in a number of different positions, said catch device having a projection, and a stop on said frame adjustable in such manner that it may be moved into and out of the path of movement of said projection and adapted upon lowering of said member to engage said projection so as to release said catch device.

110 6. In a lifting jack, the combination of a frame, a member vertically guided and movable up and down in said frame, a jack mechanism for effecting the up and down movement of said member in said frame, a rod 115
slidable vertically in said member and provided with a vertical row of teeth free from engagement with said jack mechanism, a catch device on said up and down movable member 120
adapted to engage said row of teeth

on said vertically slidable rod and thereby to lock said rod to said member in a number of different positions, a spring actuating said catch device so as to move the same into locking position relatively to said rod, said catch device having a projection, and a stop on said frame adjustable in such manner that it may be moved into and out of the path of movement of said projection and adapted upon lowering of said member to engage said projection so as to release said catch device.

7. In a lifting jack, the combination of a frame, a member vertically guided and movable up and down in said frame, a jack mechanism for effecting the up and down movement of said member in said frame, a rod slidable vertically in said member and provided with a vertical row of teeth free from engagement with said jack mechanism, a catch device on said up and down movable member adapted to engage said row of teeth on said vertically slidable rod and thereby to lock said rod to said member in a number of different positions, said catch device consisting of a pawl, a projecting arm on said pawl, and a pin on which said pawl is pivoted in the up and down movable member, and a stop on said frame located in the path of movement of said projecting arm on said pawl and adapted upon lowering of said member to engage said projecting arm to move said pawl out of engagement.

8. In a lifting jack, the combination of a frame, a member vertically guided and movable up and down in said frame, a jack mechanism for effecting the up and down movement of said member in said frame, a rod slidable vertically in said member and provided with a vertical row of teeth free from engagement with said jack mechanism, a catch device on said up and down movable member adapted to engage said row of teeth on said vertically slidable rod and thereby to lock said rod to said member in a number of different positions, said catch device consisting of a pawl, a projecting arm on said pawl, a pin on which said pawl is pivoted in the up and down movable member, and a spring actuating said pawl so as to move the same into locking position relatively to said rod, and a stop on said frame located in the path of movement of said projecting arm on said pawl and adapted upon lowering of said member to engage said projecting arm to move said pawl out of engagement.

JOHAN GUNNAR EVERSTAM.
